UNITED STATES PATENT OFFICE

RALPH E. THOMPSON, OF BROOKLINE, MASSACHUSETTS, ASSIGNOR TO GILLETTE SAFETY RAZOR COMPANY, OF BOSTON, MASSACHUSETTS, A CORPORATION OF DELAWARE

SAFETY BLADE

Application filed November 15, 1930. Serial No. 496,026.

This invention relates to razors, and relates more particularly to a safety blade for razors.

An object of the invention is to provide a 5 razor blade having a safety edge, that is, an edge which is self protected in such manner as to prevent it from cutting the skin, without materially impairing its effectiveness for shaving.

10 The ordinary type of safety razor, having a blade with two edges, is provided with a rigid guard member and a rigid cap member between which the razor blade is clamped. The arrangement of the co-operating elements of the razor is such that the blade edge is given a position, relative the guard member, which is believed to be the most satisfactory for shaving with the particular type 15 blade. Any inequalities in manufacture, however, and variations in adjustment result in the blade edges, at times, not being in their correct position relative the guards of the razors. This results in the fact that while one blade may be equally as sharp as another 20 blade, still it will not perform as satisfactorily in a razor, due to the fact that its width may vary slightly, due to manufacturing inequalities. Likewise, in clamping the holder together, one blade may fit the holder more satisfactorily than another so that the shaving edge of one blade may perform more satisfactorily than another, this regardless of the quality of the blades.

According to this invention, a blade having 25 a safety edge is provided which can be employed in, or as a part of, a razor of the open blade type, which will then have the protective quality of the safety razor, although lacking a guard considered as a part 30 distinct from, or separated from, the blade itself. The blade, according to this invention, can also be employed in a razor of any design in which a guard for the cutting edges is provided. In the latter case, the 35 razor will have an additional element of safety, which is advantageous in the case of safety razors having blades which are adjustable to vary the exposure of the blade edge. Furthermore, a safety razor blade, according to this invention, can be used in a

detachable blade razor without the necessity for a guard member, the safety edge being sufficient in itself to prevent danger of cutting the skin, and since a guard is not essential, the difficulties of correctly positioning the edge of a blade, with respect to a guard member, are avoided.

According to this invention, a razor blade is sharpened, as is customary, and after being sharpened, portions of the cutting edges 40 are built up by deposits of metal, Bakelite, or other suitable material on the cutting edge, these built up portions resulting finally in a razor blade having a large number of alternate dull and sharp portions, the dull 45 portions being the built up deposits of material with the sharpened portions between them.

The invention will now be explained with reference to the drawings, of which:

Fig. 1 is a side elevation of a portion of a razor blade, and

Fig. 2 is a transverse section on the line 2-2 of Fig. 1.

In the drawings, the numeral 3 indicates 50 a razor blade, on the sharpened edge 4 of which has been closely deposited the large number of spots of material 5. The spots 55 may be spots of metal which have been sprayed upon the edge 4, may be spots of metal which have been plated, or otherwise suitably attached, or may be drops of Bakelite lacquer, or other suitable material which has been baked upon the edge. These spots of material break up the blade in a series of 60 alternate dull and sharp portions of limited extent, of which the dull portions are located near enough together to prevent the sharp portions from entering the skin of the user, when the blade edge is presented to the 65 skin at any angle at which the skin could be cut, while permitting them to reach the beard in the act of shaving. It has been found that, in spite of the presence of the dull portions, a clean and comfortable shave 70 can be obtained from a blade of this character, it being necessary to merely repeat the stroke of the razor a few times, as is customarily done by most persons in shaving.

Whereas one embodiment of the invention 75

has been described for the purpose of illustration, it should be understood that the invention is not limited to the exact details described, as many departures may be made by 5 those skilled in the art without departing from the spirit of the invention.

It will be noted that the blade 3 may be sharpened by the usual commercial methods used in manufacturing blades because its 10 cutting edge is initially continuous and uninterrupted. It is then converted into a safety blade by having the series of curved spots or drops 5 deposited at regular intervals along its sharpened edge. It is, of 15 course, impracticable to resharpen the blade without removing the spots and so destroying its safety characteristic. The manufacturer is thus protected against improperly or unskillfully resharpened blades finding 20 their way into the market.

What is claimed is:

1. A safety razor blade having a continuously sharpened edge divided into sharpened and dull portions by spaced deposits of material 25 individually secured upon said edge.
2. A safety razor blade provided at a shaving edge with a series of alternating sharp and dull portions of limited extent, the dull portions being provided by separate deposits 30 of material individually attached to the shaving edge.
3. A safety razor blade having a sharpened edge divided into sharp and dull portions by deposits of lacquer which are baked on said 35 edge.
4. A safety blade for a razor, having a continuously beveled cutting edge and a series of rounded drops individually united thereto, overlapping said cutting edge and 40 providing collectively an interrupted guard therefore as well as a preventative for resharpening.

Signed at Boston, Massachusetts, this 14th day of November, 1930.

45 RALPH E. THOMPSON.
